(57) **CLAIM**

The ornamental design for the lamp housing, as shown and described.

DESCRIPTION

FIG. 1 is a side elevation view of the lamp housing in accordance with our design, illustrating a possible environment for the lamp;

FIG. 2 is a front elevation view of the lamp housing in accordance with our design;

FIG. 3 is a side elevation view of the lamp housing in accordance with our design;

FIG. 4 illustrates the top plan view of the lamp housing in accordance with our design; and,

FIG. 5 illustrates the bottom plan view of the lamp housing in accordance with our design.

The right and left elevation views are symmetrical and the front and rear elevation views are symmetrical.

The broken line showing of environmental structure is for illustrative purposes only and forms no part of the claimed design.
